CHARGING DEVICE FOR CASTING MACHINES

George A. Waldie, Dayton, Ohio, assignor to The Hydraulic Development Corporation, Inc., Wilmington, Del., a corporation of Delaware

Application March 21, 1942, Serial No. 435,691

6 Claims. (Cl. 22—79)

This invention relates to casting and, in particular, to charging devices for casting machines.

With certain types of die casting machines, particularly those handling brass, aluminum and magnesium, it was heretofore customary to ladle the molten metal into the machine by hand for each shot. Aside from the fact that this ladling action is rather crude and lacks accuracy, it requires the full time of an operator and, thereby, increases the cost of production.

It is, therefore, an object of this invention to provide a charging device for charging casting machines, which will overcome the above mentioned drawbacks.

It is another object of the invention to provide a device for charging casting machines, which will be operated automatically at a predetermined stage of operation of the machine to be charged.

Still another object of the invention consists in the provision of a charging device, which will make it possible automatically to charge a casting machine for each shot with a predetermined but variable quantity of molten metal.

It is another object to provide a device for charging a casting machine which, while automatically charging the machine, will prevent the slag from being filled into the machine.

Still another object consists in the provision of a device for charging casting machines, which will prevent the slag from entering the charging device.

These and other objects and advantages of the invention will appear more clearly from the following specification in connection with the accompanying drawings, in which:

Figure 1 diagrammatically illustrates a die casting machine provided with a charging device according to the invention.

Figures 2 to 5 show various stages of operation of a first embodiment of the invention.

Figures 6 and 7 show a further embodiment of the invention.

Figures 8 and 9 illustrate another embodiment of the invention, while

Figure 10 shows a detail which may be used in connection with any of the embodiments in the drawings.

Referring now to the drawings in detail, the structure shown in Figure 1 comprises a clamping cylinder 1 having reciprocably mounted therein a double-acting piston 2 connected by a piston rod 3, which latter is adapted to support a mold portion 4 for cooperation with a mold portion 5.

The mold portion 5 is stationary and connected with an injection cylinder 6 having reciprocably mounted therein an injection plunger 7. The injection plunger 7 is operated by a double-acting piston 8 reciprocable in a cylinder 9. The right hand portion of the cylinder 9 is connected with a conduit 10 leading to a four-way valve, generally designated 11, of any standard design.

10 The valve 11 is connected with a conduit 12 leading to the left hand side of the cylinder 9. Two further conduits 13 and 14 connected with the valve 11 lead to a similarly constructed four-way valve 15, which communicates through conduits 16 and 17 with the respective ends of the cylinder 1. The valve member 18 of the valve 11 is operable by a solenoid 19 so as to effect hydraulic connection between the conduits 10 and 14, while simultaneously fluid connection is established between the conduits 12 and 13. In a similar manner, the valve member 20 of the valve 15 is operable by a solenoid 21 so as to effect hydraulic connection between the conduits 16 and 14, while simultaneously connecting the conduits 13 and 17.

15 The solenoid 19 is connected with a line 22 adapted, by closure of the contactor blade 23, to be connected with the line 24. The contactor blade 23 is moved into its closing position by energization of the solenoid 25 which, when energized, also causes its contactor blade 26 to connect the line 27 with the line 28, which latter is connected to the line 24. The solenoid 25 is arranged in a line 29, one end of which is connected to the line 30 leading to the main supply line 31, while the other end of the line 29 is normally connected through switch blade 32 with the line 27.

20 The switch blade 32 is controlled by a timing device 33 which, when actuated, causes the switch blade 32, after a predetermined time corresponding to the setting of the timer, to interrupt electric connection between the lines 29 and 27. The timing device 33 is connected through line 34 with a line 35, one end of which leads to a normally open switch 36, while the other end is connected to another timing device 37.

25 The timing device 37 is connected by line 38 with the line 24 and controls the switch blade 39 normally interconnecting the lines 40 and 41. Actuation of the timing device 37 causes the switch blade 39 to break the connection between the lines 40 and 41. The line 40 is connected

with the line 24, which latter leads to the main supply line 42.

Also connected with the main supply line 42 is a line 43 adapted, by closure of the starter switch 44, to be connected with the line 45, which latter comprises a contactor solenoid 46, and leads to the main supply line 31. Branching off from the line 45 is a line 47 adapted, by closure of the contactor blade 48, to be connected with the line 41. Closure of the contactor blade 48 is brought about by energization of the solenoid 46 which, when energized, also causes its contactor blade 49 to connect the line 50, branching off from the line 24, with the line 51 comprising the solenoid 21 and leading to the main supply line 31. Branching off from the line 24 is a line 52 leading to a switch 53, similar to the switch 36. The switch 53, when closed, establishes electric connection between the line 52 and the line 54 leading to the line 29.

The hydraulic system of Figure 1 is supplied with pressure fluid from a pump 55, having its suction line 56 connected with a fluid reservoir or surge tank 57. The tank 57 is connected by conduit 58 with the conduit 13. The pressure side of the pump 55 communicates through conduit 59 with the conduit 14.

The charging or ladling device, according to the present invention, shown in Figures 1 to 5, is generally designated with the numeral 60. The charging device 60 comprises a container 61 containing molten metal 62 and supported by a support 63 forming a part of the frame 64 of the casting machine shown in Figure 1.

Pivotedly connected to the container 61 and shiftable about the pivot 65 is a ladle 66 with a cup shaped portion 67 (Figure 4) and a channel 68, communicating with the portion 67. Pivotedly connected to the ladle 66 is a link 69 which, in its turn, is pivotally connected to a rod 70 passing through a guide 71, carried by the container 61. The rod 70 is connected to a dash pot arrangement, generally designated 72, which may be of any standard design and is so constructed that it slows down the upward movement of the rod 70. The rod 70 carries a pin (Figure 5) adapted to cooperate with a lever arm 74 connected to a sleeve 75 which is shiftable about a bolt 76 journaled in the frame 64 and connected thereto by a nut 77. The sleeve 75 has furthermore connected thereto an arm 78 which carries a roller 79 for cooperation with a cam 80. The cam 80 is supported by an arm 81 which, in its turn, is connected to the plunger 7 and has an extension 82 adapted to actuate the switch 36. The cam 80 has a guiding sleeve 83 slidable on the guiding rod 84, which latter has one end connected with the mold portion 5 and the other end connected with the cylinder 9.

In order to perform a working cycle of the structure shown in Figures 1 to 5, the operator first starts the pump 55 and then closes the starter switch 44. Closure of the starter switch 44 establishes an energizing circuit for the contactor solenoid 46, which energizing circuit comprises main supply line 42, line 43, starter switch 44, line 45 including the solenoid 46 and main supply line 31. Energization of the contactor solenoid 46 causes the switch blades 48 and 49 to move into their closing position. Closure of the switch blade 48 establishes a holding circuit for the solenoid 46, which holding circuit comprises main supply line 42, line 24, line 40, switch blade 39, line 41, contactor blade 48, line 47, solenoid 46, line 45 and main supply line 31.

Closure of the contactor blade 49 closes a circuit comprising main supply line 42, line 24, line 50, blade 49, line 51, valve solenoid 21 and main supply line 31. In this way the solenoid 21 is energized and shifts the valve member 20 of valve 15 into position for establishing fluid connection between the conduits 14 and 16, while connecting the conduit 17 with the conduit 13. As a result thereof, pressure fluid from the pump 55 passes through conduits 59 and 14, valve 15 and conduit 16 into the left hand end of the cylinder 1. Here the pressure fluid acts upon the piston 2 and moves the latter toward the right so that the mold portion 4 engages the mold portion 5.

At about the time when the mold portions 4 and 5 engage each other, the arm 85, connected to the mold portion 4, engages the switch 53 so as to close the latter, thereby establishing a circuit comprising main supply line 42, line 24, line 52, switch 53, lines 54 and 29, contactor solenoid 25, line 29, line 30 and main supply line 31. As a result thereof, the solenoid 25 is energized and causes its contactor blades 23 and 26 to move into closing position.

Closure of the contactor blade 26 establishes a holding circuit for the solenoid 25, which holding circuit comprises main supply line 42, line 24, line 28, contactor blade 26, line 21, switch blade 32, line 29, solenoid 25, line 30 and main supply line 31. Closure of the contactor blade 23 establishes an energizing circuit for the valve solenoid 19, which energizing circuit comprises main supply line 42, line 24, blade 23, line 22, solenoid 19, line 30 and main supply line 31. Energization of the solenoid 19 causes the valve member 18 to move into such a position as to establish fluid connection between the conduits 14 and 10, while connecting the conduit 12 with the conduit 13.

Pressure fluid from the pump 55 now passes through conduits 59, 14 and 10 into the right end of the cylinder 9 where it acts upon the piston 8 and begins to move the latter, together with the plunger 7, toward the left. Inasmuch as the arm 81 and cam 80 are connected to the plunger, the leftward movement of the plunger 7 also causes leftward movement of the cam 80. Immediately at or shortly after the starting of the leftward movement of the piston 8, the cam 80 engaging the roller 79 begins, by means of this roller, to shift the arm 78 in anticlockwise direction, thereby rotating the sleeve 75 and arm 74 connected thereto likewise in anticlockwise direction. This causes the arm 74 to engage the pin 73 on the rod 70 and, thereby, to move the rod 70 downwardly. Downward movement of the rod 70 in its turn causes the link 69 to shift the ladle 66 in clockwise direction from the stage indicated in Figure 2 into the stage indicated in Figure 3.

The molten metal ladled by the ladle 66 will then pour through the opening 86 into the injection cylinder 6 and in front of the plunger 7. At a desired point of travel, the extension 82 on the arm 81 engages the switch 36 so as to close the latter, thereby establishing an energizing circuit for the timing devices 33 and 37. These energizing circuits respectively comprise main supply line 42, line 24, line 38, timing device 37, lines 35 and 30 and main supply line 31; and main supply line 42, line 24, line 97, timing device 33, lines 34, 30 and main supply line 31.

The plunger 7 continues its leftward movement, thereby ejecting the metal from the cylinder 6 into the mold portions 4 and 5. While the

plunger 7 performs its actual injecting operation, the cam 80 passes beyond and thereby disengages the roller 79. As soon as this happens, the weight of the cup shaped portion 67 moves the ladle 66 in anticlockwise direction so that the cup shaped portion 67 again immerses into the molten metal contained in the container 61. Movement of the ladle 66 in anticlockwise direction causes the rod 70 to move upwardly, which upward movement is somewhat slowed down by the dash pot arrangement 72, thereby preventing splashing of the molten metal in the container 61 when the ladle 66 begins to immerse.

When the time for which the timing device 33 was set has expired, the blade 32 opens, thereby breaking the holding circuit for the contactor solenoid 25. As a result thereof, the contactor blades 26 and 23 open. This results in a deenergization of the valve solenoid 19 so that spring means (not shown) in the valve 11 shifts the valve member 18 into a position in which the conduit 14 communicates with the conduit 12, while the conduit 16 communicates with the conduit 13. Pressure fluid from the pump 55 now flows through conduits 59, 14 and 12 to the left side of the cylinder 9, where it acts upon the piston 8 and begins to move the latter toward the right.

A predetermined time thereafter, also the time for which the timing device 37 was set expires, thereby causing the blade 39 to interrupt electric connection between the lines 40 and 41. This results in a deenergization of the contactor solenoid 46 so that the contactor blades 48 and 49 open.

Opening of the contactor blade 49 breaks the energizing circuit for the solenoid 21, and as a result thereof, a spring (not shown) in the valve 15 shifts the valve member 20 into a position in which the conduit 14 communicates with the conduit 17, while simultaneously fluid connection is established between the conduit 16 and the conduit 13.

Pressure fluid from the pump 55 now flows through conduits 59, 14 and 17 into the right hand portion of the cylinder 1, where it acts upon the piston 2 and moves the latter toward the left, thereby withdrawing the mold portion 4 from the mold portion 5.

While the plunger 7 is moving toward the right, the cam 80 shifts the arm 78 slightly in clockwise direction. This, however, has no effect on the rod 70. When the pistons 2 and 8 have again reached the position shown in Figure 1, the machine comes to a halt and is ready for a new cycle.

Referring now to the embodiments shown in Figures 6 and 7, the cam 80 for actuating the ladle 66 is replaced by a fluid operable auxiliary cylinder-piston-assembly, generally designated 88. More specifically, the rod 70 is connected to a piston (not shown) which is reciprocable in the cylinder 89 and is moved downwardly by fluid passing from the pump 55 through the conduit 90, four-way valve 91 and conduit 92 into the upper portion of the cylinder 89. On the other hand, the rod 70 is moved upwardly when fluid is admitted through the conduit 90 and valve 91 into the conduit 93. The valve member 94, pertaining to the valve 91, is controlled by a solenoid 95 which, when energized, causes the valve member 94 to establish fluid connection between the conduits 90 and 92, while simultaneously connecting the exhaust line 96 with the conduit 93.

The solenoid 95 has one end thereof connect-

ed with the line 97 leading to the main supply line 98, while the other end of the solenoid 95 is connected to a line 99 adapted, by closure of the contactor blade 100, to communicate with line 101 leading to the main supply line 102. The blade 100 is controlled by a solenoid 103 which, when energized, closes the blade 100 and also the blade 104. Closure of the blade 104 establishes electric connection between the line 105, connected to the main supply line 98, and the line 106 leading to a normally closed control switch 107. The control switch 107 is furthermore connected, by means of the line 108, with one end of the solenoid 103, while the other end of the solenoid 103 is connected through line 109 with the main supply line 102. The line 108 is adapted to be connected with a line 110 by closure of the switch 111.

The switch 107 is carried by a support 112 connected to the rod 70 so as to be movable therewith. The support 112 carries an extension 113 serving as a guide member for the rod 114 and adapted to engage a collar 115 adjustably mounted on the rod 114. The rod 114 has connected to the lower end thereof a float 116 which may be of solid graphite, or any other material which will stand up under the heat in the molten metal in the injection cylinder 6. The device of Figures 6 and 7 is operated in the following manner:

If it is desired to have the ladle 66 pour metal into the injection cylinder 6, the switch 111 is closed, either manually or by the extension 82 of Figure 1 when the latter has reached a predetermined point of travel on its leftward movement. Closure of the switch 111 establishes an energizing circuit for the solenoid 103, which energizing circuit comprises main supply line 98, switch 111, solenoid 103, line 109 and main supply line 102.

Energization of the solenoid 103 causes the switch blades 104 and 100 to move into their closing position. Closure of the switch blade 104 establishes a holding circuit for the solenoid 103, which holding circuit comprises the main supply line 102, line 109, solenoid 103, line 108, control switch 107, line 106, contactor blade 104, line 105 and main supply line 98. Closure of the contactor blade 100 establishes an energizing circuit for the solenoid 95, comprising main supply line 102, contactor blade 100, line 99, solenoid 95, line 97 and main supply line 98. Energization of the solenoid 95 causes the valve member 94 to move downwardly, thereby connecting the conduit 90 with the conduit 92, while simultaneously establishing connection between the exhaust line 96 and the conduit 93. Pressure fluid from the pump 55 now passes through conduit 90, valve 91 and conduit 92 into the upper portion of the cylinder 89, thereby moving the rod 70 downwardly. This movement, by means of link 69, causes the ladle 66 to shift in clockwise direction so as to pour the molten metal from the ladle into the injection cylinder 6. While the level of the molten metal in the injection cylinder 6 rises, it lifts the float 116. When the float 116 has risen to a predetermined level, corresponding to a predetermined quantity of metal in the cylinder 6, the rod 114, connected to the float 116, actuates the control switch 107 so as to open the latter, thereby breaking the holding circuit for the solenoid 103.

Deenergization of the solenoid 103 causes the contactor blades 104 and 100 to move into open position, with the result that the energizing cir-

cuit for the solenoid 95 is interrupted. Deenergization of the solenoid 95 causes a spring (not shown) in the valve 91 to move the valve member 94 upwardly thereby establishing fluid connection between the conduits 90 and 93, while connecting the conduit 92 with the exhaust conduit 96. Pressure fluid from the pump 55 now passes through conduits 90 and 93 into the lower portion of the cylinder 89 so as to lift the rod 70 which, by means of the link 69, now shifts the ladle 66 in anticlockwise direction, as indicated in Figure 7. Upward movement of the rod 70 also causes upward movement of the support 112 and, thereby, of the extension 113, which latter, when engaging the collar 115, lifts the rod 114 with the float 116 out of the injection cylinder 6. The injection plunger 7 may then perform its injection operation in a manner previously described in connection with Figure 1.

Referring now to the embodiment of Figures 8 and 9, the latter is likewise provided with a fluid operable cylinder-piston-assembly 117, similar to the cylinder-piston-assembly 88 of Figures 6 and 7. The rod 70, however, connected with a piston (not shown) in the cylinder 118, is provided with an adjustable collar 119 and has its upper end connected to a slide 120 which is slideable on rods 121 arranged in a frame portion 122. The slide 120 carries a pivot 123 connected to the ladle 66 and rotatable in a bore 124 in the slide 120. The slide 120 is furthermore provided with an abutment 125 for limiting the movement of the ladle 66 when the latter moves in anticlockwise direction. The ladle 66 is provided with an abutment 126 adapted to cooperate with the bolt 127 in a manner which will presently be described.

For actuating the device of Figures 8 and 9, pressure fluid is admitted through the conduit 93, while fluid is exhausted from the conduit 92. As a result thereof, the rod 70 and, thereby, the slide 120 connected thereto move upwardly. Upward movement of the slide 120 causes first to move the ladle 66, parallel to itself, upwardly until the abutment 126 strikes the bolt 127. From now on the upward movement of the slide 120 causes the pivot 123, connected to the ladle 66, to turn in the bore 124 so that the ladle 66 rotates in clockwise direction. When the collar 119 abuts the stationary member 128, the ladle 66 occupies the position shown in Figure 9 and cannot move further in clockwise direction. The metal will then flow from the ladle 66 into the injection cylinder 6. The highest pouring position of the ladle 66 is preferably so that some material is still left in the cup shaped portion 67 for retaining the slag of the metal.

To return the ladle 66 to its initial or immersed position, it is merely necessary to admit pressure fluid through conduit 92 while connecting the conduit 93 to an exhaust. The rod 70, together with the slide 120, will then move downwardly and the ladle will again occupy the position shown in Figure 8.

In instances in which it is desired to substantially prevent the entrance of any slag into the ladle, the ladle may be constructed as shown in Figure 10. As will be seen therefrom, the upper end of the cup shaped portion 67 of the ladle is closed by a closure member 129, while an opening 103 is provided at a lower part of the cup shaped ladle portion. The opening 130 is adapted to be closed by a sliding valve member 131, reciprocable in a guiding portion 132 of the

cup shaped portion 67. The valve member 131 has connected thereto a U-shaped member 133, which embraces a ball joint 134 connected to a rod 135. The rod 135 forms an extension of the member 136 which is shiftable about a pivot 137. The member 136 is threadedly engaged by a threaded bolt 138 carrying a ball shaped float 139.

The arrangement is such that the float 139, when contacting the bottom 140 of the cup shaped portion 67, causes the joint 134 to open the bore 130 to a maximum extent so that the molten metal in the container 61 will enter the interior of the cup shaped portion. While the metal level in the cup shaped portion 67 rises, the float 139 likewise rises and moves about the pivot 137 so that the joint 134 gradually decreases the free section of the opening 130. When the level of the metal in the cup shaped portion 67 has reached a predetermined height, corresponding to the quantity desired to pour into the casting machine, the joint 134 has completely closed the opening 130. The ladle may then be lifted in any of the ways described in connection with Figures 1 to 9 for transferring the metal from the ladle 66 into the casting machine.

The arrangement of Figure 10 also makes it possible, by adjustment of the bolt 138, to vary the quantity of molten metal ladled by the ladle 66 when immersed into the metal in the container 61.

A further advantage of the structure shown in Figure 10 consists in that practically no slag can enter the cup shaped portion 67.

It will be understood that I desire to secure within my invention such modifications as come within the scope of the claims and the invention.

Having thus fully described my invention, what I claim as new and desire to secure by Letters Patent, is:

1. A charging device comprising in combination, storage means adapted to receive molten metal, a charging member pivotally movable selectively into a first position for dipping into said storage means to receive molten metal, or into a second position for discharging metal thus received, a slide, pivot means pivotally connecting said charging member to said slide, said slide being operable to move said charging member parallel to itself out of said container, fluid operable means operable selectively to actuate said slide, and means operable at a predetermined point of travel of said slide and responsive to the travel of said slide to cause said charging member to shift about said pivot means for discharging metal from said discharging member.

2. In combination, storage means adapted to receive molten metal, a charging member movable selectively into a first position for dipping into said storage means to receive molten metal, or into a second position for discharging metal thus received, a slide pivotally connected to said charging member and operable to move said charging member parallel to itself out of said storage means, fluid operable means for actuating said slide, means operable at a predetermined point of travel of said slide and responsive to the travel of said slide to cause said charging member to move through a predetermined angle for discharging metal therefrom, and means associated with said slide for varying said predetermined angle.

3. In combination, storage means adapted to

receive molten metal, a charging member operable automatically to transfer molten metal from said storage means into a chamber, means responsive to a predetermined filling of said chamber for interrupting the discharge of molten metal from said charging member into said chamber, and means responsive to the said interruption for returning the metal, remaining in said charging member, to said storage means.

4. In combination, storage means adapted to receive molten metal, a charging member movable selectively into a first position to dip into said container for receiving molten metal therefrom, or into a second position for unloading the thus received metal into a chamber, reciprocable pressure fluid operable means operatively connected with said charging member for actuating the same, and control means associated with said reciprocable means actuated by a predetermined discharge of molten metal into said chamber for terminating the unloading action of said charging member and causing actuation of said fluid operable means for returning the charging member to said first position.

5. In combination, storage means adapted to receive molten metal, a charging member movable selectively into a first position to receive molten metal from said storage means, or into a second position to unload the thus received metal into a chamber, actuating means for moving said

charging member selectively into said first or said second position, control means associated with said actuating means and operable in response to a predetermined quantity of molten metal received by said chamber for initiating the return of said charging member into said first position, and means associated with said control means and operable to vary said predetermined quantity of molten metal necessary in said chamber for initiating the return of said charging member into said first position.

6. A charging device comprising in combination, a container for receiving molten metal, a charging member movable selectively into a first end position to receive molten metal from said container, or into a second end position to discharge the thus received metal, fluid operable means for selectively moving said charging member from said first position into said second position, or vice versa, electrical means for controlling the actuation of said fluid operable to move said charging member into said second position, and means actuated by a determined discharge of metal from the charging member for rendering said electrical means operably ineffective upon said fluid operable means to cause the latter to move said charging member into said first position.

GEORGE A. WALDIE.
